UNITED STATES PATENT OFFICE.

BERNHARD KRÄMER, OF CHARLOTTENBURG, GERMANY, ASSIGNOR TO GENERAL ELECTRIC COMPANY, A CORPORATION OF NEW YORK.

FUEL-PULVERIZER FOR INTERNAL-COMBUSTION ENGINES.

1,142,440.

Specification of Letters Patent. Patented June 8, 1915.

Application filed August 15, 1912. Serial No. 715,220.

To all whom it may concern:

Be it known that I, BERNHARD KRÄMER, subject of the Emperor of Germany, and residing at Charlottenburg, Germany, have 5 invented certain new and useful Improvements in Fuel-Pulverizers for Internal-Combustion Engines, of which the following is a specification.

The present invention relates to fuel pulverizers or injectors for internal combustion engines of the type wherein each successive charge of fuel, such as crude oil for example, is injected by a blast of high pressure air into a body of compressed air in the 10 combustion space of the engine cylinder, which compressed air has been previously heated by compression due to the piston or pistons to a temperature above the igniting temperature of the fuel.

20 The object of my invention is to improve the construction and operation of such pulverizers or atomizers, particular reference being made to the means of supporting and securing the same in place.

25 For a consideration of what I believe to be novel and my invention, attention is directed to the accompanying description and the claims appended thereto.

In the accompanying drawings, which 30 illustrate one of the embodiments of my invention, Figure 1 is an axial section through the pulverizer and the cylinder of the engine; Fig. 2 is a cross section taken on line 2—2 of Fig. 1, and Fig. 3 is a cross section 35 taken on line 3—3 of Fig. 1.

5 indicates the cylinder of an internal combustion engine, which may be horizontally or vertically disposed. In the present embodiment of the invention the cylinder is 40 intended to occupy a vertical position. Located within the cylinder are two pistons (not shown), which move in opposite directions and are connected to the same crank-shaft. Formed integral with the cylinder is 45 a projection 6 that is recessed or bored centrally to receive the pulverizer means, as will appear later. The cylinder is also provided with an annular jacket 7, and between the jacket and the cylinder is a chamber 8 through which cooling water circulates. It 50 is to be noted that the projection 6 extends through the jacket 7 and is separated therefrom by an annular space 9. By reason of this construction the cylinder, which is sub-

jected to different temperatures than the 55 jacket, is free to expand and contract with temperature changes without being modified or restricted in any way by the jacket. This arrangement has the advantage that the cylinder will not be distorted in the region of 60 the pulverizer or atomizer, and hence interfere with the proper working of the pistons. That is to say, if it were not for this construction and the jacket and cylinder were rigidly united in the region of the 65 pulverizer means, the difference in temperature between said parts would in many cases force the cylinder out of line or cause some part of the structure to break. As will appear later, the pulverizer and the parts associated therewith are all mounted in the projection 6, so that its distortions do not affect the alignment of the working parts. This is a very important feature, since all of the parts of the pulverizer means must fit 70 with great exactness.

10 indicates a soft packing which is situated in an annular recess formed partly in the projection 6 and partly in the jacket 7. Its object is to prevent water from leaking 80 out of the cooling chamber 8 through the clearance or space 9. The packing is confined by an annular plate 11 that is secured in place by stud bolts 12, the latter being threaded into the jacket. 85

Located in the recess in the projection 6 is a casing 13, that is provided with a conical-ended surface 14 that makes a tight fit with a corresponding surface in the cylinder wall. This casing is held in position by a 90 number of bolts 15, of which four are shown. It will be noted that these bolts enter the projection so that if the latter is distorted in any direction, the position of the casing will be correspondingly changed and 95 the alignment of the parts preserved.

The casing 13 is bored centrally to receive the pulverizer 16, which is made in two principal parts. The main portion thereof is provided with a beveled or inclined end 17, that snugly fits a correspondingly shaped surface in the casing. The periphery of the pulverizer is provided with a plurality of axially extending ribs 18, between which are passages for conveying compressed air under high pressure, commonly referred to as the "air blast". The pulverizer is also provided with a 195

screw threaded portion 19 to receive a tool, by means of which it can be removed. The end of the pulverizer adjacent the cylinder is provided with a plurality of diagonal openings or passages 20 that converge toward a common point, and through which oil is discharged into the cylinder. As shown, some of these passages are arranged to discharge heavy oil and the other or others to discharge a lighter oil. The lighter oil may be used only in starting or it may be used continuously as desired. In the present embodiment of my invention only one passage 21 is provided for the light oil 10 which is in communication with the annular chamber 22, the latter receiving oil from the passage 23. The passages receiving heavy oil are in communication with the chamber 24, the latter receiving oil from the passage 25. The passages 23 and 25 are provided with check valves 26, Fig. 2, which prevent the air blast under any condition from blowing oil back through the supply pipes 27 and 28, or, in other words cut off 20 the blast pressure from the supply pipes and the pumps. The pipe 27 is connected to a pump for supplying the light oil and the pipe 28 to a pump for supplying the heavy oil. Air for forcing fuel into the cylinder is supplied by pipe 30 which is connected to a compressed air receiver of suitable construction. Air from this pipe enters the passage 31, which is in communication with the air chamber 32. This chamber is annular in form, and its center is eccentrically disposed to the axis of the pulverizer, as best shown in Fig. 2. Located within the pulverizer is a needle valve 33 whose inner end is tapered to conform to the shape of 30 the seat in the pulverizer and is also hardened to reduce wear. Apparatus of this character is subjected to very high pressures, for example the fuel pressure may be 1350 lbs. per square inch and the air blast pressure 900 to 1200 lbs. per sq. inch. These pressures vary of course under different conditions and with different machines. From these illustrations it will be seen that the parts must not only be well made and accurately fitted at the start to keep the joints and seats pressure tight but that the construction must be such that said relation will be preserved. In order to keep the parts pressure tight, the inner end of the main 40 part of the pulverizer has been made conical. The opposite end is made in the form of a nut 34, which is seated on the face of the casing 13. It is preferable to insert a soft copper washer 35 in this joint to insure a tight fit. Between the nut and the other portion of the pulverizer is a stiff compression spring 36 which at all times presses the main portion 16 of the pulverizer against its seat. The outer end of said portion is reduced in cross section and fits the bore of the 50

nut 34. In this bore is located a suitable packing 37 that is held under compression by the nut 38. By reason of the construction described it will be seen that a tight joint is maintained between the nut 34 and the casing and also between the inner end of the pulverizer and the casing. 70

In order to properly distribute the mixture of fuel and blast air within the combustion space a flame plate 39 is provided which is held in place by a ring nut 40. In the flame plate are two or more radial openings 41 through which the mixture of fuel and air passes. 75

Mounted on the casing containing the pulverizer is a frame 42 which carries a pivot or fulcrum 43 for the lever 44, the latter actuating the needle valve 33. By preference this fulcrum is made in the form of an eccentric, the end parts 45 of which are cylindrical, so that by rotating the eccentric portion about the axis of the parts 45, the lever 44 as a whole can be moved in the direction of its length, thus permitting the timing of the needle valve 33 to be changed; that is to say, the valve can be made to open earlier or later with respect to the dead center position of the cranks on the main shaft. To facilitate this adjustment the pivot is provided with a plate 46, Fig. 3, 80 containing a pin 47 that is adapted to be inserted in any one of the holes 48 shown in dotted lines Fig. 1. One end of the lever is provided with a roller 49 that is adapted to roll on the fuel cam 50, the latter being 85 driven by the cam shaft 51 that is geared to the main shaft of the engine. The other end of the lever 44 is provided with a fork 52 that embraces the needle valve 33 and is provided with a removable wearing plate 53 that engages a spherical surfaced piece 54. The part 54 is seated in a cupped out portion of the hub of the valve guide 55. The object of this arrangement is to prevent the parts from binding and obviate any interference with the free operation thereof. Between the lever and the nut 38 is a coiled compression spring 56 that tends at all times to hold the parts in the position shown. The guide 55 is cylindrical in form and is located in a projection 57 of the frame. 90

The frame projection 57 is screw threaded to receive the spring holder 58. The left hand end of the compression spring 59 rests on an abutment 60 that enters the outer end of the spindle of the needle valve 33. The other end of the spring engages the abutment 61, said abutment being adjusted by the screw 62. To the abutment 60 is attached an indicator 63, the free end of which 100 extends outwardly through the adjusting screw 62, so that the operation of the needle valve can be observed and its length of movement easily measured. 110

It will be observed that the pulverizer, the 120

needle valve and the actuating mechanism therefor (with the exception of the cam 50) are mounted on the projection 6 of the cylinder, so that, no matter in which direction the said projection is distorted, it will in no way affect the alignment of the parts and hence troubles incident to the cramping or binding of the parts are obviated. By making the pulverizer in two principal parts as described and locating a spring between them, tight joints are provided where necessary, and if one part of said pulverizer is injured it can be replaced without the other, thereby effecting a saving in cost.

By arranging the parts as shown and described, the needle valve can be made relatively short which is desirable from a manufacturing and operating standpoint.

At the same time the parts are simple, easily manufactured and not liable to get out of order.

In accordance with the provisions of the patent statutes, I have described the principle of operation of my invention, together with the apparatus which I now consider to represent the best embodiment thereof; but I desire to have it understood that the apparatus shown is only illustrative and that the invention can be carried out by other means.

What I claim as new and desire to secure by Letters Patent of the United States is:

1. In an engine of the character described, the combination of a cylinder having an outwardly extending recessed projection, a jacket for the cylinder having an opening through which the projection extends, said opening being of greater diameter than the projection whereby said projection and jacket are capable of independent movements, a pulverizer means located in said recess for discharging fuel into the cylinder, a conduit for supplying fuel to said means, a conduit for supplying a blast of air to said means at a pressure greater than the compression pressure in the combustion space of the cylinder, and means for securing the pulverizer means in said projection.

2. In an engine of the character described, the combination of a cylinder having an outwardly extending recessed projection, a cooling jacket for the cylinder having an opening through which the projection extends, said opening being of greater diameter than the projection whereby said projection is free to move with respect to the cooling jacket under temperature changes, a packing for the joint between said projection and the jacket, and a pulverizer means for injecting fuel into the combustion space of the cylinder which is located in the recess and is supported solely by the projection.

3. In an engine of the character described, the combination of a cylinder, a water

jacket surrounding it and having an opening, a recessed projection supported solely by the cylinder and projecting through said opening, said opening being of greater diameter than said projection so as to permit relative independent movements of the jacket and projection under expansion, a casing located in said recess and supported solely by said projection, a pulverizer located in said casing, conduits conveying fuel and air under high pressure thereto, a needle valve in the pulverizer controlling the admission of fuel to the combustion space of the cylinder, a frame also carried by the projection, a lever supported by the frame for opening the valve, and a cam for actuating the lever.

4. In an engine of the character described, the combination of a cylinder having an exterior projection on one side containing an opening communicating with the cylinder, a water jacket surrounding the cylinder having an opening of greater cross-sectional area than that of the projection and through which the projection extends, a casing, means for attaching the casing to the projection so that it may move therewith, a pulverizer in the casing under the influence of temperature changes, a needle valve that extends through the pulverizer for controlling the admission of fuel to the combustion space of the cylinder, a guide for the valve, a lever for actuating the valve, a spring for closing the valve, and a frame that carries the guide, spring and lever and is itself supported by the projection.

5. In an engine of the character described, the combination of a casing having a conical ended bore, a pulverizer mounted therein which fits said bore, said pulverizer having a flange within the bore, a retaining nut that is seated pressure tight on the casing, a coiled compression spring located between the nut and the flange for holding the pulverizer against its seat, and a valve for controlling the passage of fuel from the pulverizer.

6. In an engine of the character described, the combination of a casing having a conical ended bore, a pulverizer mounted therein which fits said end, a retaining nut, a coiled compression spring located between the nut and the pulverizer which hold the latter against its seat, a needle valve which passes through the pulverizer and the nut, a packing for the valve stem, a means for actuating the needle valve, and conduit means for admitting fuel and a gas to the pulverizer.

7. In a fuel injector for an internal combustion engine, the combination of a casing containing a pulverizer, a needle valve for controlling the passage of fuel that extends through said pulverizer, a frame mounted on the casing, a guide for the outer end of the needle valve carried by said frame, a

means which acts to close said needle valve also carried by said frame, a lever for actuating said valve pivoted on said frame and acting on the valve between said guide and said pulverizer, and a part interposed between said lever and an abutment associated with the valve adapted to slide with reference to the lever when the same is

rocked and simultaneously to rock with reference to the abutment in a bearing therein. 10

In witness whereof I have hereunto set my hand.

BERNHARD KRÄMER.
